DESIGN FOR A TOY

Arthur J. Bruns, Los Angeles, Calif.

Application April 10, 1944, Serial No. 113,204

Term of patent 3½ years

(Ch. D34—15)

To all whom it may concern:

Be it known that I, Arthur J. Bruns, a citizen of the United States of America and a resident of Los Angeles, in the county of Los Angeles, State of California, have invented a new, original, and ornamental Design for a Toy, of which the following is a specification, reference being had to the accompanying drawing, forming a part thereof; and in which,

The figure is a perspective view of the toy showing my new design. The appearance of the opposite side of the article is the same as that of the side shown.

I claim:

The ornamental design for a toy, as shown and described.

ARTHUR J. BRUNS.
